GEORGE F. DE WEIN, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

TRIMMER-SAW.

1,083,006.

Specification of Letters Patent.

Patented Dec. 30, 1913.

Application filed December 13, 1912. Serial No. 736,843.

To all whom it may concern:

Be it known that I, GEORGE F. DE WEIN, a citizen of the United States, residing at Milwaukee, in the county of Milwaukee and 5 State of Wisconsin, have invented a certain new and useful Improvement in Trimmer-Saws, of which the following is a specification.

This invention relates to improvements 10 in the construction of sawmill machinery and particularly to improvements in mechanism for controlling the position of a plurality of trimmer saws, or similar apparatus.

The object of the invention is to provide 15 a controlling means for positioning a plurality of trimmer saws or similar apparatus, by means of which the saws are normally individually controllable and which, under certain conditions of operation, permits 20 either collective or selective control of the positions of the saws, irrespective of the position of the individual saws at the time such actuation is desired.

The device of the present invention permits 25 positioning of a plurality of saws from a common operating stand and utilizes fluid pressure, preferably air, for moving the saws to their respective desired positions, the valves controlling the fluid pressure 30 means being either directly operated or indirectly by means of wires.

As the number of saws in various trimmer saw equipments is a variable quantity for 35 different mills, it is desirable to have a controlling mechanism which may be conveniently extended to include any number of individual saw positioning mechanisms, and it is an object of the present invention to provide such a convenient means of extension. It is also desirable in mechanisms of 40 this character to have similar working parts interchangeable with each other, and it is a feature of the present invention to so construct the elements that the number of 45 different parts of the mechanism is reduced to a minimum, thereby facilitating the furnishing of repair parts.

The market is at present being supplied 50 with two general types of fluid pressure actuated positioning means for trimmer saws. In one of these, the saws are moved into operative position by admitting fluid pressure against pistons which force the saws toward the table in opposition to the 55 action of weights which normally tend to

withdraw the saws from operative position. In the other type, the saws are forced into operative position by the action of gravity and are withdrawn from the table by means of fluid pressure admitted against pistons. 60 It is an object of the present invention to provide a controlling mechanism which will operate efficiently upon either of these standard types of trimmer saw positioning mechanisms, with but a very slight change 65 in the pipe connections leading to the controlling mechanism.

Although the present invention is disclosed as specifically applied to the positioning mechanism for trimmer saws, it is not 70 desired to limit same to such application, as its utility would be equally great in other arts, such as the controlling of electric circuits and similar apparatus.

A clear conception of several embodiments 75 of the controlling mechanism as applied to trimmer saw control, may be had by referring to the accompanying drawings in which like reference characters designate the same or similar parts in the various views. 80

Figure 1 is a transverse vertical section through one of the individual controlling mechanisms of a trimmer saw equipment, showing the collective and selective controlling means in mid position. Fig. 2 is 85 an end view of the trimmer saw controlling mechanism showing the collective controlling means in operative position. Fig. 3 is a transverse vertical section through one of the individual controlling mechanisms of 90 a trimmer saw equipment, showing the selective or slasher saw controlling means in operative position. Fig. 4 is a front view of a fragment of the trimmer saw controlling mechanism, showing a section through 95 several of the individual valves and valve casings, the section being taken along the line IV—IV of Fig. 3 looking in the direction of the arrow. Fig. 5 is a showing of the general arrangement of one type of trimmer saw equipment, showing the position of the controlling mechanism relative to the saws and table. Fig. 6 is a fragmentary end view of a modified form of controlling means for trimmer saws, showing a transverse vertical section through a fragment 105 of one of the individual controlling valves and valve casing, and showing the collective and selective controlling means in mid position. Fig. 7 is a fragmentary end view of 110

a modified form of controlling means for trimmer saws, showing the collective controlling means in operative position. Fig. 8 is a fragmentary end view of a modified 5 form of controlling means for trimmer saws, showing the selective or slasher saw controlling means in operative position. Fig. 9 is a diagrammatic showing of another type of trimmer saw equipment.

10 The devices disclosed in the drawings are applicable, as shown in Figs. 1 to 8, to that type of trimmer saw actuating mechanism in which the individual saws are forced into operative position by means of fluid pressure 15 acting against pistons and in opposition to gravitating weights which normally tend to later explained, it will be noted that by a hold the saws out of operative position. As slight change of the connections leading 20 from the actuating cylinders to the valve casing, the device as disclosed in Fig. 9 is equally efficiently applicable to that type of apparatus in which the saws are normally held in operative position by gravity and 25 withdrawn from operative position by the fluid pressure. By the use of the term collective, is meant all of the saws operable by the mechanism, while the term selective is used to indicate a predetermined allotment 30 or proportion of the total number of saws.

An equipment of trimmer saws in a sawmill generally consists of a conveying table 53 upon which the material to be sawed is fed toward the saw by means of a conveying 35 chain or belt 54 actuated by means of drums 55, see Fig. 5. The individual saws 47 are carried by arms 48 which are pivoted to suitable supporting beams. The common power shaft 52 carries a series of suitable 40 driving pulleys 51 which are connected with suitable driving means on the saw shaft by means of belts 50. The location of the pivots of the arms 48 is such that with the saws 47 in operative position 45 the belts 50 are taut and with the saws 47 in inoperative position the belts 50 are flexed. The individual saw positioning cylinders 41 are stationarily supported upon suitable timbers and carry actuating pistons 42 which are connected with the saw arms 48 by means of connecting rods 43, 49. The 50 levers 44 are fulcrumed at the stationary pivots 45, being connected with adjacent ends of the connecting rods 43, 49, at one 55 end and carrying adjustable weights at their opposite ends. It should be noted that with fluid pressure established within the cylinders 41 and above the pistons 42, the saws 47 will be forced toward the table 53 against 60 the action of the gravitating weights 46 which normally tend to keep the saws 47 in inoperative position or away from the table 53.

In the controlling mechanism disclosed in 65 Figs. 1, 2, 3 and 4, the valve casing is

formed of a series of individual similar valve boxes 23 and covers 20 which are secured to the boxes 23 by means of bolts 21 or other suitable means. These similar valve boxes 23 and covers 20 are placed end to end and are clamped between end casing portions 38 of the valve casing by means of through bolts 24. The number of boxes 23 and covers 20 corresponds to the number of saws in the set, there being one valve box 75 23 for each saw 47. The pressure chamber 22 extends throughout the entire length of the valve casing and is connected to a suitable source of fluid pressure supply by means of a pipe 37 which may connect with 80 either of the end portions 38 of the casing. It will be noted that by providing an individual valve box 23 for each of the individual trimmer saws 47, the casing may readily be extended to include any desired 85 number of saws.

The valves 28, 30, are supported on surfaces within the pressure chamber 22 and control ports directed toward the interior of this pressure chamber. The valves 28, 30, 90 are normally pressed to their seats by the pressure within the chamber 22. The ports leading to the pressure chamber 22 are three in number for each individual valve box 23, and consist of a central or exhaust port 29 95 which connects directly with the atmosphere, and two end ports. One of these end ports is normally closed by means of a plug 26, and the other connects with the positioning cylinder 41 of its respective individual saw by means of a pipe 25. The valves 28, 30, are movable over the pressure controlling ports by means of suitable valve stems 31 which are reduced in diameter at their mid portions. The reduced portions 100 of each stem 31 is fitted into a recess formed in the upper portion of its respective valve 28, 30. This construction permits free automatic adjustment of the valves 28, 30, to 105 their corresponding seats, to compensate for 110 wear. The portions of the valve stems 31 which pass through the valve boxes 23 are suitably packed by means of stuffing boxes 27, 36. The operating ends of the valve stems 31 are provided with adjustable cap 115 screws 40 over which the actuating levers take during actuation of the valves.

The valve actuating mechanism consists of individual intermediate controlling levers 6 having fins or projecting portions 16 and 120 having downwardly extending valve actuating arms 14, and individual slasher controlling levers 7 having fins or projecting portions 17 and having downwardly extending valve actuating portions 15. These 125 levers 6, 7, are exactly alike but differ in their relative locations upon the lever supporting shaft 13 thus making the levers interchangeably reversible. The levers 7 correspond to the saws 47 which it is de- 130

sired to operate selectively or as slasher saws. The levers 6 correspond to the intermediate saws 47 which it is desired to have in inoperative position during the operation of the selective or slasher saws. The individual levers 6, 7, are provided with suitable numbers indicating the respective individual saws 47 which they control, see Fig. 4. The arms 14, 15, of the levers 6, 7, have forked ends which take over the cap screws 40 of the stems 31. The lever supporting shaft 13 is mounted in bearings 18 formed on the end cover plates 39, which plates are secured to the end portions 38 of the valve casing. The collective and selective controlling levers 8 are mounted to swing upon overhanging ends of the shaft 13, and are connected by means of a pair of rods 9, 11, which are parallel to each other and span the gap between the levers 8. The levers 8 are normally held in mid position by means of suitable springs 19 secured to the cover plates 39 and having notches indicating various operating positions, which coact with the pins 35, see Figs. 1, 2, 3 and 4. Pins 34 are secured to the levers 8 and carry blocks 32 which coact in parallel sided slots formed in corresponding ends of the levers 12. The levers 12 are pivoted at their mid positions by means of pivots 33 fixed to the bearings 18 of the cover plates 39. The upper ends of the levers 12 are connected by means of a rod 10. In the modified form of saw controlling mechanism as disclosed in Figs. 6, 7 and 8, the individual controlling levers 56, 57, are provided with hubs through which the common lever supporting shaft 63 passes. The collective and selective controlling levers 58 are supported upon a shaft 61, the shafts 61, 63 being mounted in bearings formed in the frame 62. The valve casings and valve mechanisms of this modified controlling means are identical with those disclosed in Figs. 1, 2, 3 and 4, with the exception that the pipes 25 which connect with the saw positioning cylinders 41 connect with the pressure chamber 22 through the ports which in the former disclosure were closed off by means of plugs 26, while the ports on the other sides of the exhaust ports 29 are closed by means of plugs 26. The individual controlling levers 56 are provided with selective controlling pins 96, and with collective controlling pins 86. The individual controlling levers 57 are provided with selective controlling pins 97 and collective controlling pins 87. Each of the individual levers 56, 57, is provided with a slotted valve actuating portion 67 which coacts between the head of the cap screw 40 and the end of the valve rod 31. The collective and selective controlling levers 58 are connected by means of parallel collective

controlling rods 59, and selective controlling rods 60, which span the gap between these levers 58.

During the normal operation of the trimmer saws 47, and at such times as it is not desired to operate the saws selectively, the controlling levers 8 are in mid position as disclosed in Fig. 1. With the levers 8 in mid position the individual levers 6, 7, are free to be thrown to either of the extreme operating positions. With the individual levers 6, 7, in the position with the handles to the right, the valves 28, 30, of the respective levers permit free exhaust of fluid from the interiors of the corresponding saw positioning cylinders 41 through the pipes 25 to atmosphere through the exhaust ports 29, see Figs. 1 and 5. The gravitating weights 46 then cause the levers 44 to swing about the pivots 45 and to withdraw the saws 47 from the table 53, at the same time flexing the belts 50. If any of the levers 6, 7 are thrown to the position with handles to the left as shown in Fig. 1, the corresponding valves 28, 30, are shifted to the extreme right of the pressure chamber 22 and the pipes 25 and cylinders 41 are placed in direct communication with the pressure chamber 22. The exhaust ports 29 are at the same time cut off from communication with the pipes 25, thus permitting fluid under pressure to act through the pipes 25 against the pistons 42 and in opposition to the action of the weights 46, to force the saws 47 toward the table 53 and into operative position.

If it is desired to suddenly withdraw all of the saws collectively from operative position, it is necessary to throw the levers 8 from the mid position indicated in Fig. 1 to the collective controlling position indicated in Fig. 2. With the levers 8 in collective controlling position, all of the individual levers 6, 7, are forced to their extreme positions to the right of the center line by means of the collective controlling rod 9, which during the movement of the levers 8 is brought in contact with the individual levers 6, 7, near the mid portions thereof, and forces these levers 6, 7, to the extreme position indicated in Fig. 2. It will be noted that during collective control by motion of the levers 8 to the right of normal position, the selective controlling rods 10, 11, advance to positions of disengagement relative to the projecting portions 16, 17, of the individual levers 6, 7. After operation of the collective controlling levers 8, it is desirable to bring these levers 8 back to mid position as indicated in Fig. 1, in order to have the levers 8 in such position as to permit free actuation of the individual levers 6, 7, and also so as not to require excessive movement of the levers 8 when later operating the selective control.

If it is desired to operate the selective or slasher saws, it is necessary to throw the levers 8 from the mid position as shown in Fig. 1 to the selective controlling position indicated in Fig. 3. During this movement of the levers 8, the rods 11 which are carried by the levers 8 come in contact with the edges of the projecting portions 17 of the levers 7, and carry these levers 7 to the extreme left or saws down position. Simultaneously with the motion of the levers 7 to saws down position, the rod 10 carried by the levers 12, is swung about the pivots 33 by means of the pins 34 and intermediate blocks 32, causing all of the levers 6, which are otherwise positioned to take the extreme right or saws up position. The movement of the levers 6 to saws up position is accomplished by the automatic coaction of the rod 10 with the projecting portions 16 of the levers 6. The use of the intermediate blocks 32, provides a means for preventing excessive wear along the working surfaces of the pins 34 and levers 12. The blocks 32 during movement of the levers 8, simultaneously slide upon the plane surfaces of the recess formed in the ends of the levers 12 and rotate about the pins 34 to compensate for the changes in angularity between the levers 8, 12.

It should be noted that the only individual levers 6, 7, which are affected by motion of the levers 8 in either direction, are those corresponding to the saws 47 which at the time are in other than the desired positions; that is, if one of the slasher saws 47 is at the time in slasher position and it is desired to operate all of the slasher saws 47, the individual actuating lever 7 corresponding to that particular slasher saw will not be moved; and if one of the intermediate saws 47 is in inoperative position at the time, the individual actuating levers 6 corresponding to that particular intermediate saw will not be disturbed by actuation of the levers 8 to slasher position.

During the normal operation of the modified device disclosed in Figs. 6, 7 and 8, the levers 58 are in the mid position as disclosed in Fig. 6. The individual levers 56, 57, are then free to be moved to either of the extreme positions disclosed. With the individual levers 56, 57, in the position with handles to the left as shown, the valves 28, 30, are to the extreme left and the pressure chamber 22 is connected through the pipes 25 to the interiors of the saw positioning cylinders 41. With the levers 56, 57, in the position with handles to the right as shown in Fig. 6, the valves 28, 30, are to the extreme right and the pipes 25 are connected to atmosphere through the exhaust ports 29. It should be noted that due to the shifting of the valve operating portion of the levers 6,

7, 56, 57, from the ends of the levers 6, 7, 56 as disclosed in Figs. 1, 2, 3, and 4, to a position intermediate the ends of the levers, the required direction of motion of the valves 28, 30, with the two types of levers, is reversed for a similar direction of motion of the operating ends of the levers 6, 7, 56, 57, during operation of the individual controlling means. It is desirable to maintain the operating movements of the individual levers 6, 7, 56, 57, the same in all cases, preferably toward the operator while bringing the saws into operative position and away from the operator while withdrawing the saws from operative position. This will be hereinafter discussed with relation to the various types of trimmer saw.

With the levers 58 in mid position as shown in Fig. 6, the rods 59, 60 are in normal inoperative position. The two positions of each of the pins 96, 97, indicate the two positions of these pins with their respective levers 56, 57, in each of the two extreme positions. If a lever 56 with its corresponding pin 96 is thrown to the position with handle to the right as shown, its corresponding pin 96 takes a position of engagement with the rod 60. If the lever 57 with its corresponding pin 97 is thrown into the position with handle to the left as shown, its corresponding pin 97 moves to a position of engagement with the rod 60.

If it is desired to move all of the individual saws 47 simultaneously and collectively away from the table 53, the levers 58 are thrown to the position to the extreme right of normal, as indicated in Fig. 7. During the movement of the levers 58 to the right, the rod 59 comes in contact with the pins 87, 86, carried by the levers 57, 56, respectively, which are not in saws up position, causing these pins 87, 86, and their corresponding levers 57, 56, to take the position indicated in Fig. 7. The pins 96, 86, of all of the levers 56 then take corresponding positions, while the pins 97, 87, of all of the levers 57 likewise take corresponding positions, as shown in Fig. 7. All of the valves 28, 30, are then located in their extreme right position and the pipes 25 are connected with the exhaust through the ports 29, the saws 47 being in inoperative position.

If it is desired to operate the selective or slasher saws, the levers 58 are thrown to the extreme left position, as indicated in Fig. 8. During such movement of the levers 58, the rod 60 is forced inwardly against surfaces of the pins 96, 97, causing the pins 96, 97, to spread and the individual levers 56, 57, which are not in the desired position, to move to the positions indicated in Fig. 8. With the pins 96, 97, and the pins 86, 87, in the respective positions as indicated in Fig. 8, the corresponding respective individual

levers 56, 57, are in the positions of saws down and saws up, respectively.

The individual levers 56, 57, of the modified device are interchangeable as in the device disclosed in Figs. 1, 2, 3 and 4, but the positions of the pins 87, 86, must be altered to make the same angle with the levers on the other side thereof. The general construction of the valves and valve 10 casing of the modified device is, however, identical with that of the device disclosed in Figs. 1, 2, 3 and 4, thereby maintaining the advantages of interchangeability of these members throughout.

15 In order to apply the controlling mechanism disclosed in Figs. 1 to 8, to that type of trimmer saw equipment in which the saws 47 are moved into cutting position by gravity and out of cutting position by fluid 20 pressure, it is necessary to either reverse the individual valve boxes 23 themselves by swinging same 180° about a vertical axis without disturbing the porting, or to reverse the ports connecting the pipes 25 with the 25 chamber 22, relative to the valves 28, 30. The reversal of the ports is accomplished by interchanging the connections of the plugs 26 and pipes 25 with the valve boxes 23. In either case the lever location as well as the 30 central position of the exhaust ports 29 relative to the valves 28, 30, is maintained, the location or hand of the port connecting the pipe 25 with the chamber 22 being reversed relative to the valves 28, 30. With the 35 valves 28, 30, Fig. 9, of this type of equipment to the extreme right and using the class of levers 6, 7, as disclosed in Figs. 1, 2, 3 and 4, the pipes 25 and actuating cylinders 410 are in communication with the 40 exhaust ports 29. The pistons 42 and connecting rods 430 then permit the weight of the saws 47 and the elements connected therewith to move the saws 47 into cutting position. By moving the valves 28, 30, to 45 the extreme left, the communication between the pipes 25 and the ports 29 is cut off and pressure is admitted directly from the chamber 22 through the pipes 25 to the under faces of the pistons 42, thereby moving the 50 saws 47 out of cutting position.

It will thus be noted that the control device is readily applicable to various types of trimmer saw equipments without changing the direction of actuation of the individual levers 6, 7, as referred to their effect on the position of the saws 47. The use of interchangeable and reversible valve boxes 23 and ports connecting therewith, also permits the use of operating levers of any of 55 the three general classes of levers, two of which are disclosed. It should also be noted that if it is desired to reverse the normal direction of operation of the operating levers, this may readily be done on either

type of equipment without changing the location of the levers relative to the valve boxes, by reversing the position of the ports connected with the pipes 25, relative to the valves 28, 30. The individual valve boxes 23 may be considered as having one handed 70 ports and capable of having the hand, or location of the ports, relative to the central exhaust ports 29, altered by swinging the boxes 180° or by reversing the plug and pipe connections without changing the location of the levers 6, 7. During installation the same change may be effected by similarly swinging the boxes collectively. The general construction and arrangement of the manually operable and pressure controlling 80 means provide great flexibility in the mechanism and adapt same for use with all types of equipments.

It should be understood that it is not desired to be limited to the exact details of 85 construction shown and described, for obvious modifications will occur to a person skilled in the art.

It is claimed and desired to secure by Letters Patent,—

90 1. In combination with a table, a plurality of saws movable into and out of cutting position relative to said table, individual means for normally setting each of said saws in either of said two positions, and means for 95 effecting direct selective setting of said saws from any position of prior individual setting.

100 2. In combination with a table, a plurality of saws movable into and out of cutting position relative to said table, individual means for normally setting each of said saws in either of said two positions, and common means for effecting collective and direct selective setting of said saws from any position of prior individual setting.

110 3. In combination with a table, a plurality of saws movable into and out of cutting position relative to said table, manually operable individual levers for normally setting each of said saws in either of said two positions, and a common manually operable lever for effecting collective and direct selective setting of said saws from any position of prior individual setting.

115 4. In combination with a table, a plurality of saws movable into and out of cutting position relative to said table, individual levers for normally setting each of said saws in either of said two positions, a valve operable by each of said levers, an individual valve box for each of said valves, said valve boxes abutting to form a common communicating passage, and a pressure inlet to said common passage.

120 5. In combination with a table, a plurality of saws movable into and out of cutting position relative to said table, pressure means

- for moving said saws into one of said two positions, individual means for controlling the setting of each of said saws in either of said two positions, and means for maintaining the direction of operation of said individual means as referred to their effect on the position of said saws irrespective as to whether the pressure means move said saws into or out of cutting position.
- 5 6. In combination with a table, a plurality of saws movable into and out of cutting position relative to said table, pressure means for moving said saws into one of said two positions, individual levers for controlling said means, and means for maintaining the direction of operation of said levers as referred to their effect on the position of said saws irrespective of the class of said individual levers.
- 10 7. In combination with a table, a plurality of saws movable into and out of cutting position relative to said table, pressure means for moving said saws, individual means for setting each of said saws in either of said two positions, a valve operable by each of said individual means for controlling said pressure means, porting controllable by said valves, and means for altering the position of said porting as referred to said valves.
- 15 8. In combination with a table, a plurality of saws movable into and out of cutting position relative to said table, pressure means for moving said saws, individual means for setting each of said saws, valves operable by said individual means for controlling said pressure means, a casing forming a common chamber in which said valves are operable, ports communicating with said chamber and
- 20 controllable by said valves, and means for permitting reversal of the position of said ports relative to said valves.
- 25 9. In combination with a table, a plurality of saws movable into and out of cutting position relative to said table, pressure means for moving said saws, individual means for setting each of said saws, valves operable by said individual means for controlling said pressure means, a valve casing for said valves, ports in said casing controllable by said valves, and means permitting altering the position of said casing as referred to the position of said individual operating means.
- 30 10. In combination with a table, a plurality of saws movable into and out of cutting position relative to said table, pressure means for moving said saws into one of said positions, individual means for setting each of said saws in either of said two positions, valves operable by said individual means for controlling said pressure means, and a plurality of ports controllable by each of said valves, one of said ports being central relative to the movement of said valve and the other of said ports having its position relative to said central port alterable.
- 35 11. In combination with a trimmer saw, a lever interchangeably reversible to convert a saw from slasher to intermediate or vice versa.
- In testimony whereof, the signature of 70
the inventor is affixed hereto in the presence
of two witnesses.
